Atty.

UNITED STATES PATENT OFFICE.

FRED L. CIZEK, OF CEDAR RAPIDS, IOWA.

COMBINED SCREEN AND STORM DOOR.

1,415,920.

Specification of Letters Patent. Patented May 16, 1922.

Application filed November 29, 1921. Serial No. 518,672.

To all whom it may concern:

Be it known that I, FRED L. CIZEK, a citizen of the United States, residing at Cedar Rapids, in the county of Linn and

5 State of Iowa, have invented certain new and useful Improvements in Combined Screen and Storm Doors; and I do hereby declare the following to be a full, clear, and exact description of the invention, such as 10 will enable others skilled in the art to which it appertains to make and use the same.

This invention relates to the construction of storm and screen doors, and the object of the invention is to provide such doors with 15 simple and efficient means for fastening removable screened or glazed panels in place in such doors, so that the door may be easily and quickly changed from a screen door, for summer use, to a storm door, for winter use, 20 or vice versa.

The invention is fully disclosed in the description and claims following, reference being had to the accompanying drawing, in which:

25 Fig. 1 is an elevation of a door embodying my invention. Fig. 2 is a section illustrating the invention, on the line 2—2 of Fig. 3. Fig. 3 is a section on the line 3—3 of Fig. 2. Fig. 4 shows a modified form of 30 fastener, detached.

In the drawing, the numeral 5 denotes an auxiliary door, which is rabbetted at 6 to receive inset screen frames 7, or glazed sash 8. At suitable holding points, preferably 35 about four, as shown, holes 9 are bored in the door-stiles, and partly in the inset screen or storm-sash frame, as best shown in Fig. 3, to receive a large-bodied, deeply threaded screw 10. Across the partial hole in the 40 frame is made a saw-kerf 11, and in this is set a strip 12 of metal, of suitable thickness to be engaged by the screw at one side, as shown. The strip is best attached by forming tangs 12^a thereon, and driving it in place 45 in the saw-kerf. It then bridges the partial hole in the frame, and serves as a clamping plate to bind the frame snugly in its seat.

Its length gives it a considerable bearing along the wood and tends to prevent splitting of the wood under the strain of the fastener, or otherwise.

50 The screw has a suitable head, preferably flat underneath as shown in Fig. 3, which has less tendency to split the wood than the countersunk type of head shown in Fig. 4. 55 This figure illustrates an expedient for avoiding the cutting of a deep thread, by securing to the screw-shank, as by welding, a short coil of stiff wire 10^a, which performs the same function as does the screw in Fig. 3, 60 drawing the parts together by the turning of an inclined member under the clamping strip.

65 In practice the panels should be inserted on the inner side of the door, with fasteners on the same side, so that when the door is hooked the panels cannot be unlawfully removed from the outside.

Having thus described my invention, I claim:

70 1. The combination with a door, rabbetted to receive screen or storm-sash, and bored to receive fasteners, of sash partially bored coincidently with the door, clamping-plates set across said partial boring, and deeply-threaded fasteners set in the bored holes, and intercepting the clamping-plates at one side.

75 2. Combined with a door, rabbetted to receive screen or storm-sash, and bored adjacent to the rabbets for fastening members, 80 insertable sash, partially bored, coincidently with the door the borings of the sash being crossed by saw-kerfs, tanged metal strips driven therein, and turnable fasteners seated in the bored holes, and having inclined lateral extensions to engage said strips.

85 In testimony whereof I affix my signature in presence of two witnesses.

FRED L. CIZEK.

Witnesses:

F. W. ARMSTRONG,
D. L. WOOD.
